EMANUEL INGHAM, OF SAN DIEGO, CALIFORNIA.

METHOD AND APPARATUS FOR WEAVING TEXTILE FABRICS.

1,328,794.

Specification of Letters Patent. Patented Jan. 20, 1920.

Application filed October 17, 1917. Serial No. 197,128.

To all whom it may concern:

Be it known that I, EMANUEL INGHAM, a subject of the King of Great Britain, and resident of San Diego, county of San Diego, 5 State of California, have invented certain new and useful Improvements in Methods and Apparatus for Weaving Textile Fabrics, of which the following is a specification.

10 This invention relates to weaving, and more particularly to a method and apparatus for weaving textile fabrics, especially curved fabrics.

In its broader aspects, the improved 15 method of weaving comprehended in the present invention is applicable to the production of fabrics of any shape or material, but more specifically the invention contemplates the production of fabrics C-shaped 20 in cross-section, suitable for use in the manufacture of pneumatic tire casings. Such fabric can be employed either as a textile foundation, embedded in rubber, to form the casing itself, or as a lining, or as a 25 protective or anti-slipping covering for tires.

Among the objects of the invention are, 30 to provide novel means for weaving without the use of a shuttle, such means comprising instead a needle of special design for laying the weft, whereby the simplicity and speed of the loom is greatly increased, especially for coarse work; and to provide means for producing indefinite lengths of 35 woven fabric, curved in cross-section and also curved longitudinally, such fabric, as it comes from the loom, conforming to the shape of a tire, thus obviating the necessity for pressing or molding the fabric, as has been the usual custom heretofore. So far 40 as I am aware, I am the first to propose the weaving of a fabric of double curvature, as described.

In order that the various features of the 45 invention may be readily understood, reference is had to the accompanying drawings, forming part of this specification, and in which,

Figure 1 is a side elevation of a weaving 50 machine or loom constructed in accordance with the invention;

Fig. 2 is a fragmentary vertical section through the needle and associated parts;

Fig. 3 is a front elevation of an enlarged 55 scale of the improved heddle which I employ;

Fig. 4 is a vertical section on the line 4-4 of Fig. 3;

Fig. 5 is a detail perspective view of one section of the heddle and the operating means therefor; 60

Fig. 6 is a vertical section through the machine substantially on the line 6-6 of Fig. 1, looking in the direction of the arrows;

Fig. 7 is an enlarged fragmentary rear 65 elevation of the warp supporting frame and weft engaging hooks or detents, the fabric being shown in section;

Fig. 8 is a similar view on a smaller scale showing the operating mechanism for the 70 hooks;

Fig. 9 is a schematic view on a small scale illustrating the relation of the needle to the warp threads;

Figs. 10 and 11 are front and rear elevations respectively of the needle, on an enlarged scale;

Fig. 12 is an edge view of the needle partly in section on the line 12-12 of Fig. 11; and

Fig. 13 is a perspective view of the needle. 80

Heretofore, so far as I am aware, in all the various attempts which have been made to produce woven textile fabrics, circular or C-shaped in cross section, a shuttle of one form or another has always been employed. The problem of replenishing the shuttle with thread has always been and still is a very vexing one and numerous inventions have been devised to facilitate this operation. The inherent defects of a 85 shuttle in this respect become particularly marked when coarse or heavy thread is used for the weft, for in such cases it is possible to wind but a comparatively small amount of thread on the bobbin carried by the 90 shuttle. 95

Probably the most striking departure from former practice which characterizes the present invention is that in producing such fabrics I propose to eliminate the shuttle entirely and to lay the weft thread in the shed of the warp by means of a specially constructed oscillating curved needle. By this means the weft thread can be carried upon a large fixed reel located at any desired point, and the thread led from such reel to the needle by which it is laid back and forth around a form across the warp. 105

I also believe it to be broadly new with me to weave a textile fabric curved or U-shaped in cross section and also curved longitudinally as it comes from the loom. In producing such a fabric the warp threads are supported around a curved frame and a 110

special heddle mechanism having radially disposed wires is provided for producing the shed.

With the above preliminary remarks I will now proceed to describe the construction of a machine in which the above principles are embodied. Referring to the drawings in detail, 1 designates a suitable base on which are supported frame members 2 and 3.

- 5 10 A main shaft 4 is journaled in the lower part of such frame members and carries at its outer end a belt pulley 5 by means of which the machine is driven. On the shaft 4 are also rigidly secured a pair of mutilated 15 beveled gears 6 and 7, each having teeth extending substantially half way around the same, as shown. These beveled gears are adapted to mesh with a beveled pinion 8, secured to a short vertical shaft, journaled 20 in the frame 2 and carrying at its upper end a second beveled pinion 9. This is adapted to mesh with a beveled gear 10 mounted on the end of a horizontal shaft 11. This shaft 11 at its forward end is journaled 25 in a bearing 12 supported at the center of a circular frame 13 supported on a suitable pedestal and secured to the frame member 3. A sleeve 14 surrounds the shaft 12, throughout the greater part of its length and 30 carries at its forward end a spider 15 having four or more thin radial arms of a length substantially equal to the radius of the needle hereinafter described, and adapted to engage the rear edge of such needle.
- 35 Warp threads are supplied from a series of reels 16, suitably supported, and such threads, designated by 18, are led first through a pair of holes in a tension ring 17 and thence through a suitable spreader 19 40 to the heddle mechanism. Such heddle mechanism, which forms one of the principal features of the invention, is illustrated in detail in Figs. 3, 4 and 5. Referring to these figures, it will be seen that the mechanism 45 comprises a circular frame or ring 21 having holes through which freely slide the outer ends of radially disposed heddle rods or wires 22. For the purpose of illustration, only a comparatively few of such wires are 50 shown, but it will be understood that in practice any desired number may be employed so as to support the warp threads as close together as may be necessary, to produce a fabric of the requisite density. As 55 clearly shown in Figs. 4 and 5, the heddle rods 22 are arranged in two sets or series disposed in different planes. The rods have eyes 23 to receive the threads and are firmly set at their inner ends into segment-shaped 60 blocks 24. It will be seen that these blocks are arranged in pairs and are pivoted at 65 to double crank arms 26. The blocks of one series are secured to the front of such crank arms, while the blocks of the other series are secured to the rear thereof. The crank arms

26 are secured to shafts 27 and the blocks 24 are provided with recesses 24^a to fit around such shafts when the crank arms are in the position shown in the drawings. It will be understood that it is necessary to provide 70 only the rear series of blocks 24 with the curved recess 24^a to fit around the shaft 27, but for practical manufacturing reasons both sets of blocks are made alike so that they are interchangeable. The recesses 24^a 75 in the front series of blocks are, however, without function. A suitable number of such shafts 27 are provided and are disposed in the arc of a circle and journaled in a fixed bracket 29 having a pedestal 30 supported 80 upon the frame member 3. The shafts 27 extend through such bracket and each has secured to its rear end a pinion 28, as clearly shown in Fig. 5. These pinions are adapted 85 to mesh with a relatively large internal gear 31, having a flange embracing the bracket 29 and rotatable thereon. To the rear side of the gear 31 is secured a plate 32 having a depending arm 34 by means of which the gear 31 is operated, as herein-after described. It will be understood, that 90 the entire heddle mechanism fits loosely over the sleeve 14, a suitable opening in the bracket 29 and plate 32, as indicated at 95 33 being provided for this purpose. 95

The lower end of the depending arm 34 carries a cross pin 35. The forward end of this pin is adapted to be engaged by a lever 36 pivoted to the pedestal 30 at 37 and the rear end of the pin 35 is adapted to be engaged by an arm 38 secured to a gear wheel 39 journaled on a stud 40 supported by the frame member 3. This gear wheel also carries a pin 41 at a point diametrically opposite to the arm 38, such pin being adapted 100 to engage the lower end of lever 36 so as to rock the same on its pivot. It will thus be seen that as the wheel 39 revolves, the arm 34 and with it the plate 32 and the gear 31, will be first oscillated in one direction by 105 means of the arm 38 and then, after the wheel 39 has made a half revolution, oscillated in the other direction by means of the pin 41 striking the lever 36. As the internal gear 31 is thus oscillated the pinions 28 will 110 be simultaneously rotated first in one direction and then in the other, the extent of oscillation of the gear 31 being such as to turn the pinions 28 and the attached crank arms 26 through 180°. As a result of such 115 rotation of the pinions and arms 26, it will be seen that the front series of segmental blocks 24 is first moved radially outward, while the blocks of the rear series are moved radially inward, as shown in the drawing, 120 and then, at the end of the next oscillation, the front series of blocks are moved radially inward and the rear series moved radially outward. The warp threads being led alternately through heddle wires supported by 125 130

the front and rear series of blocks respectively, it is obvious that the alternate radial movement of the blocks and heddle rods, as described, will result in the formation of a 5 curved or circular shed. This is indicated in Figs. 1 and 2.

The wheel 39 meshes with and is driven by a pinion 42 secured to the shaft 4.

The sleeve 14 carries a pin 43 which is 10 engaged by the slotted end 44 of a lever 45 pivoted at 46 to the frame member 2 and carrying at its other end a roller 47. This roller 47 is arranged to engage the edge of a cam wheel 48 rigidly secured to the shaft 15 4 and provided with a pair of bevel ended notches 49. As the wheel revolves the roller 47 is caused to drop into and ride out of these notches, being urged toward the cam wheel by means of a bow spring 50 secured 20 to the stud 40 by means of a bolt 51. The free end of the spring 50 bears against the lower end of the lever 45, as clearly shown in Fig. 1. It will be therefore seen that each time the roller 47 drops into a notch 25 49 the sleeve 14 will be shifted quickly to the left, thus bringing the spider 15 sharply against the rear side of the needle 52 now to be described.

In order to avoid the use of a shuttle, as 30 mentioned in the first part of this specification, I employ the novel needle device shown in detail in Figs. 9 to 13. Although such needle may be very slightly eccentric or spiral, it is shown in the drawings as circular and mounted upon a substantially true center. The needle, which is designated in its entirety by the reference character 52, consists of a flat annular member secured to a hub 53 and supported by means 40 of a single spoke or arm 55 which is attached to the needle body at its heel 56. The hub 53 is provided with an axial key-way 54, by means of which it is suitably keyed to the shaft 11 but is free to move 45 longitudinally thereon. The needle has a free end or point 57 which is preferably wedge shaped or sharpened, as shown, so as to facilitate its entering the shed of the warp, and between such point and the 50 rounded heel 56 is a gap or slot 58 through which the warp threads pass. As shown in Fig. 12, the body of the needle is itself preferably wedge-shaped in cross-section, the front edge 52^a being relatively thin and the rear edge 52^b being thicker. It will be 55 understood that the width of the needle may be made as great as desired, this being determined by the strength and rigidity which it is necessary for the needle to have. At 60 the forward edge adjacent the point 57, the needle is provided with a slight extension or projection 59 through which extends the thread delivery eye 60. This eye extends transversely of the needle to a point near its center where it merges into a groove and

joins a circumferential groove 61 extending around the periphery of the needle body. Adjacent the heel an opening 62 extends from the groove 61 through the body of the needle to the inside thereof and the hub 53 70 is also provided with a thread guiding eye 63. The weft thread 64 which is supplied from a fixed reel 65 located at any desired point, is led through the eye 63, through the opening 62, and thence follows the groove 75 61 around the circumference of the needle to the eye 60 and is delivered from such eye at approximately the most forward point of the projection 59.

As clearly shown in Fig. 2, the needle 52 80 is of such size as to just snugly fit over the circular frame 13 around which the warp threads are supported and the needle is adapted to enter the shed of the warp, as illustrated in this figure and in Fig. 9. 85

In order to properly catch and hold the weft threads at the edges of the fabric I provide the mechanism illustrated in detail in Figs. 7 and 8. Referring to these figures, 66 designates a cam secured to the shaft 4 90 at its forward end and on this cam rides a roller 67 carried at the lower end of a plunger 68 around which is disposed a helical spring 69. The upper end of the plunger 68 is pivotally connected to a pair of 95 toggle levers 70, each of which is pivoted at its free end at 71 to a hook or detent 72 pivoted at 73 to the frame 13. These hooks or detents 72 are adapted to engage the loops 74 formed in the weft threads at the 100 edges of the fabric, as shown in Fig. 7 and when moved to the position shown in dotted lines in Fig. 7, to release or cast off such loops. The cam 66 is so shaped that the movement of the detents 72 relative to the 105 needle will be properly timed.

A spring 75 is interposed between the hub 53 of the needle and the bearing 12 (see Fig. 2) so as to return the needle to its normal position after it has been forced forward by the spider 15. 110

In order to sustain the fabric and hold it in shape as it leaves the needle and curved frame 13, I provide an arc-shaped shield or support 77, preferably formed of thin sheet 115 metal and secured at its rear end to the frame 13, said frame having formed integral therewith a forwardly extending bracket 76 adapted to support such shield. Within the shield 77 and adapted to move 120 freely relative to the same is disposed a form 78 similar in shape to the tire for which the fabric is intended. This form 78 is supported on one or more spokes 79 secured to a suitable hub and loosely journaled on a shaft 80. The spokes 79 also carry an arc-shaped segment 81 on which lies a strap 82 carrying at its free end a weight 83 which serves to exert the proper tension on the fabric and warp threads, as 130

will be obvious. Also mounted on the shaft 80 is a ratchet wheel 89 and a circular rack 91, rigidly united. On the shaft 4 is mounted a cam 85 adapted to engage a lever 86 pivoted at 87 to the frame member 3 and carrying at its free end a pivoted pawl 88 adapted to engage the ratchet wheel 89. A fixed pivoted pawl 90 also engages such ratchet wheel to prevent the backward rotation thereof.

10 A latch 92 carried by one of the spokes 79 is arranged to engage the rack 91 and such latch may be operated by means of a handle 94 and link 93, said link being surrounded by a helical spring 95 which serves to keep the latch in engagement. It will be understood that as the shaft 4 rotates the pawl 88 is reciprocated, thus giving a forward step-by-step movement to the form 78, such movement being in the direction in which the weight 83 tends to urge the form. After the form has moved to the desired extent it may be set back toward the position shown in Fig. 1 by means of the latch 92. Thus 15 while the ratchet wheel 89 and rack 91 revolve continuously in one direction, the form 78 may be released from and locked to such wheels as desired, in order to secure a proper take-up of the material. The form 78 is provided near its inner side with a series of pins or hooks 84 adapted to engage the loops formed in the edge of the fabric and it will be understood that as the form moves to the left and downwardly, as seen in Fig. 1, the 20 fabric slips along over the surface of the shield 77. The chief function of the shield is to support the fabric and bridge the gap between the circular frame 13 and the end of the form 78 when the latter is in its lower 25 positions.

25 A brief description of the operation of the machine as a whole will now be given. As the shaft 4 revolves, an alternating rotary motion is given to the shaft 11 and the needle 52 which is keyed thereto. The warp threads having been led through the heddle mechanism above described are secured to the form 78 by any suitable means, such threads preferably passing through an opening in a die plate 20 which surrounds the circular frame 13. As the needle oscillates, it will enter the shed, as illustrated in Figs. 2 and 9, part of the warp remaining on the outside of the needle and part passing to the 30 inside of the needle. The weft thread is thus laid by the needle in the shed of the warp, such thread being delivered from the eye 60 at the point 59. At the end of each complete oscillation of the needle the weft thread is engaged by the hook or detent 72 and on the return stroke a loop of weft thread is formed around such detent, as shown in Fig. 7. It is obvious that it is necessary for the needle to make a complete 35 oscillation in one direction and return to its

starting point so as to be completely withdrawn from the shed before the shed changes, and therefore it is apparent that two weft threads will be laid side by side in each shed of the warp. It will also be clear 78 that at one edge of the fabric the weft is looped around the warp thread, thus forming a true selvage, while at the other edge a series of loops is formed, as shown in Fig. 7. It will also be understood that while both 78 of the detents 72 move together, only one is operative at any one time, the weft threads being caught first by the hook on one side and then by the hook on the other side, as the needle oscillates back and forth. The 80 fact that the warp threads 18 are held under tension by the mechanism above described, enables such threads to strip the loops 74 from the detents, as such detents are moved outwardly.

85 After each oscillation of the needle and therefore after the laying of every pair of weft threads, the spider 15, through the mechanism above described, gives the needle a sharp blow, thus driving it to the left and beating up the weft tightly into the fell of the fabric. After each such movement the spring 75 returns the needle to normal position.

90 It will be observed that the frame 13 and needle 52 are disposed at the same distance from the axis 80 as is the form 78, and lie in a plane substantially radial to such axis, and perpendicular to the median line of said form. The weft threads are therefore laid 95 in true radial planes, and as they extend entirely across or around the fabric from one edge to the other, they will necessarily be crowded more closely together at the inside or heels of the tire fabric than at the tread 100 portion thereof. This results in a strong tendency for the woven fabric to retain its curved shape after it leaves the form 78 and when my improved fabric is woven in indefinite lengths, it will curl itself into a 105 spiral or helix. When using the fabric in tire manufacture a suitable length will be cut off and the ends spliced together to form a complete annulus.

110 What I claim is:

1. In a loom, the combination with a curved form, and means for supporting warp threads therearound, of a rigid annular needle constructed to lay weft threads around such form across the warp and disposed in a plane extending transversely of such warp.
2. In a loom, the combination with means for supporting warp threads so as to conform to the arc of a circle, of a similarly shaped rigid annular needle mounted with its center on the axis of such circular warp, and adapted to lay weft thread across the same.
3. In a loom, the combination with means 130

- for supporting warp threads and for forming a substantially cylindrical shed, of a curved oscillatory needle adapted to enter such cylindrical shed and lay weft thread therein, said needle being mounted with its center on the axis of said cylindrical shed.
4. In a loom, the combination with means for supporting warp threads so as to define a curved surface, of means for forming a shed, and an annular oscillatory needle adapted to lay weft thread in such shed, said needle lying in a plane extending transversely of the warp threads and having a gap through which such threads pass.
- 10 5. In a loom, the combination with means for supporting warp threads so as to form a curved surface, of means for producing a shed in such warp, and an annular needle lying in a plane transverse to said warp threads adapted to enter said shed and lay weft thread therein, said needle having a gap through which the warp threads pass, and a point having a weft thread delivery eye adjacent said gap.
- 15 6. In a loom, the combination with means for supporting warp threads so as to form a curved surface, of means for producing a shed in such warp, and an annular needle having a point adapted to enter said shed and carry the weft thread therethrough, said needle being disposed in a plane transverse to said warp threads and having a gap through which such warp threads pass.
- 20 7. In a loom, the combination with means for supporting warp threads so as to form a curved surface, of means for producing a shed in such warp, and an annular needle adapted to enter said shed and lay weft thread therein, said needle having a gap, and a point adjacent such gap, said point having an eye, and the body of the needle having a circumferential groove around which the weft thread passes on its way to said eye.
- 25 8. In a loom, the combination with means for supporting warp threads and forming a shed, of a fixed reel, and a needle adapted to lay weft thread from said reel in such shed, said needle being flat and extended in a direction parallel with the warp threads, and relatively thin in a direction at right angles thereto, so as to easily enter the shed, and having a thread delivery eye opening out through its edge.
- 30 9. In a loom, the combination with means for supporting warp threads and forming a shed, of a fixed reel, a needle adapted to enter the shed, means for moving said needle transversely of the warp so as to cause it to lay weft thread from said reel in such shed, and means for moving the needle longitudinally of the warp so as to drive the weft threads together.
- 35 10. In a loom, the combination of means for supporting warp threads around a circu-
- lar frame, and forming a shed therein, of a fixed reel, an annular needle provided with a point adapted to enter the shed and having an eye through which weft thread is delivered from said reel, means for oscillating 70 said needle so as to cause it to lay weft threads across the warp in such shed, and means for shifting said needle longitudinally of the warp so as to cause it to beat up the weft threads into position.
- 75 11. In a loom, the combination with means for supporting warp threads and forming a shed, of a fixed reel, a needle adapted to enter the shed, means for moving said needle in a fixed plane transversely of the warp so 80 as to cause it to lay weft thread from said reel in such shed, means for shifting the needle longitudinally of the warp so as to beat up the weft thread into the fell of the fabric, and automatic means for returning 85 the needle to normal position after each such beating stroke.
12. In a loom for weaving fabrics C-shaped in cross-section, the combination with means for supporting warp threads to form a 90 curved surface, of means for forming a shed, a pair of movable detents disposed one adjacent each edge of such warp, a curved oscillatory needle for laying weft thread back and forth through the shed and looping it around such detents, and means for moving said detents to withdraw them from the loops thus formed.
13. In a loom for weaving fabrics C-shaped in cross-section, the combination 100 with means for supporting warp threads to define a curved surface, of means for forming a shed, a moveable detent disposed adjacent one side of such warp, a curved oscillatory needle for laying weft thread 105 back and forth through the shed and looping it around said detent, such weft thread forming a true selvage edge at the other side of the warp, and means for automatically moving said detent to withdraw it 110 from the successive loops thus formed.
14. In a loom for weaving circular fabrics, the combination with means for supporting warp threads to define a curved surface, of means for forming a shed, a 115 movable detent adjacent such warp, a curved oscillatory needle for laying weft thread back and forth through the shed and looping it around said detent, and means for automatically moving said detent to cause it 120 to cast off the loops thus formed.
15. In a loom, for weaving curved fabrics, a heddle comprising a plurality of radially disposed rods arranged around the arc of a circle and having thread receiving eyes, 125 and means for simultaneously shifting all of said rods in two groups alternately radially inward and outward to form the shed.
16. In a loom for weaving curved fabrics, 130

- 6
- a heddle comprising a plurality of radially disposed rods having thread receiving eyes intermediate their ends arranged around the arc of a circle, the outer ends of said rods being free, a guide frame through which such free ends of the rods loosely slide, and means attached to the inner ends of said rods for shifting them simultaneously radially inward or outward.
17. In a loom for weaving curved fabrics, the combination with a curved frame around which the warp threads are supported, of a similarly curved oscillatory needle adapted to lay weft threads in a fixed plane around said frame and across the warp, and a centrally pivoted segmental annular form having one end in position to receive the woven fabric as it comes from such frame, said needle and frame lying in a plane substantially radial to the pivotal axis of said form.
18. In a loom for weaving curved fabrics, the combination with a curved frame around which the warp threads are supported, of means for laying weft threads in a fixed plane around said frame and across the warp, and a segmental annular form having one end in position to receive the woven fabric as it comes from such frame, said frame lying in a plane substantially radial to the center of curvature of said form.
19. In a loom for weaving curved fabrics, the combination with a curved frame around which the fabric is woven, of a segmental annular form having one end in position to receive the fabric as it comes from such frame, said form being pivotally supported on a central axis.
20. In a loom for weaving curved fabrics, the combination with a curved frame around which the fabric is woven, of a segmental annular form having one end in position to receive the fabric as it comes from such frame, said form being pivotally supported on a central axis, and means for moving such form about its axis in a direction away from said circular frame.
21. In a loom for weaving curved fabrics, the combination with a curved frame around which the fabric is woven, of a segmental annular form having one end in position to receive the fabric as it comes from such frame, said form having a series of pins adapted to engage the edge of the fabric, and being pivotally supported on a central axis. 55
22. In a loom for weaving curved fabrics, the combination with a curved frame around which the fabric is woven, of a segmental annular pivoted form having one end in position to receive the fabric as it comes from said frame, and a thin, fixed curved shield bridging the gap between said frame and form, and overlying the latter. 60
23. In a loom for weaving curved fabrics, the combination with means for supporting warp threads, and mechanism for laying weft threads transversely across the same, of a segmental annular pivoted form in position to receive the fabric as it is woven, and a thin, fixed, curved shield bridging the gap between the weaving mechanism and said form, and overlying the latter. 65
24. In a loom for weaving curved fabrics, the combination with a curved frame around which the fabric is woven, of a fixed shield attached to and conforming to the shape of said frame, and also curved longitudinally, said shield serving to support the woven fabric as it comes from said frame. 75
25. In a loom for weaving curved fabrics, the combination with a frame around which the fabric is woven, of an arc-shaped fixed support having one end in position to receive the fabric as it comes from such frame, and means for gradually feeding the fabric circumferentially along such arc-shaped support. 80 85

EMANUEL INGHAM.
